(57) CLAIM

The ornamental design for a front face for a vehicle wheel, as shown and described.

DESCRIPTION

A portion of the disclosure of this patent document contains material which is subject to copyright protection. This patent document may show and/or describe matter which is or may become trade dress of the owner. The copyright and trade dress owner has no objection to the facsimile reproduction by anyone of the patent disclosure as it appears in the Patent and Trademark Office patent files or records, but otherwise reserves all copyright and trade dress rights whatsoever.

The single FIGURE is a front perspective view of a front face for a vehicle wheel in accordance with my new design.

It will be understood that the broken lines presented in the drawing show portions of a vehicle wheel and form no part of the claimed design.
